UNITED STATES PATENT OFFICE.

JOHANN PUPPE, OF BRESLAU, GERMANY.

PROCESS OF ROLLING BARS OR GIRDERS OF I, H, U, OR LIKE SECTION.

1,076,784.

Specification of Letters Patent. Patented Oct. 28, 1913.

Application filed July 1, 1912. Serial No. 787,101.

To all whom it may concern:

Be it known that I, JOHANN PUPPE, a subject of the German Emperor, residing at 43 Auenstrasse, Breslau, Germany, have 5 invented new and useful Improvements in the Process of the Rolling of Bars or Girders of I, H, U, or like Section, of which the following is a specification.

This invention relates to a new and improved process in the rolling of bars and girders of I, H, U or like section.

According to one known method of rolling bars or girders of I or H section, the bars or girders are rolled to the required size of 15 the web and the flanges in ordinary grooved rolls, the passes of which are so shaped as to produce a double Y section. The flanges are then straightened by means of a special finishing roll having coating horizontal 20 and vertical rolls.

Another known method consists in producing bars of double Y section in universal rolling mills whereby the edges of the flanges are acted upon simultaneously by 25 the horizontal and vertical rolls of the universal stands while being in their inclined positions with regard to the central web. According to the second method too, the flanges are finally straightened in a finishing universal roll. Both known methods 30 have the feature in common that the edges of the flanges are rolled while the flanges are in their inclined positions with regard to the central web, so that both the web and 35 the flanges are practically rolled to the required size while the beam has a double Y section, and the straightening of the flanges is effected by a single pass in a special mill after the beam has been rolled to the required size.

According to both known methods, practically the whole rolling operation applies to a beam of double Y section and the straightening of the flanges, so as to make 45 them lie one plane, represents only the final and not very important step of the process, since the beam is already rolled to the required dimensions before the final operation takes place.

50 The known method in which the main universal roll effects only the reduction of the thicknesses of the web and the flanges, and the second stand of rolls serves for shaping the edges of the flanges, while the flanges 55 are in their inclined position with regard to the web, has the disadvantage that the

forces acting upon the blank do not produce a compression of the material of the flanges, but serve mainly to bend the flanges outwardly or in themselves. This is particularly the case when the width of the flanges is very considerable.

It is not possible with the known methods to make the edges of the flanges parallel to the web as the edge of the roll which 60 presses upon the ends of the flanges must be sufficiently inclined to prevent sliding of the flange outwardly. It might of course be attempted to avoid the bending of the flanges due to the inclined pressure by the 65 employment of lateral, suitably formed, vertical rolls. This arrangement, however, has two disadvantages. The vertical rolls must not be higher than the corresponding dimension of the final pass, and fins will 70 therefore be formed upon the outside of the flanges during the first passes. It is also necessary to adjust the vertical rolls after 75 each pass in the vertical direction, or to raise the bottom horizontal roll after each 80 pass. This manner of remedying the disadvantages of the known method leads therefore to considerable complications, whereas according to the invention the smooth vertical rolls of the second stand 85 remain in their vertical position and need be adjusted only in the horizontal direction, which can be done by very simple mechanical means. Another disadvantage lies in the fact that the inclined faces of the rolls which 90 act upon the edges of the flanges exert only an indirect pressure. Owing to this indirect pressure and the inclined position of the flanges the material of the flanges is not sufficiently worked upon, more especially 95 the outer portions of the flanges do not get any compression. The outer portions of the flanges are, however, subjected to the greatest strains, so that it is of the utmost importance that the material of the flanges should be thoroughly worked through and 100 compressed during the rolling operation.

Metallographic cuts show that the material of the web of beams rolled in universal mills is very close and compact owing to 105 the direct pressure exerted upon the web during the rolling, while the material of the outer portions of the flanges shows a far less close structure.

In the accompanying drawings which 110 illustrate my invention in more or less diagrammatical fashion, Figure 1 shows the

set of rolls for rolling an unfinished I beam with outwardly bent flanges, employed in the first step of the process, Fig. 2 shows the set of rolls for straightening out the flanges, employed in the second step of the process, Fig. 3 shows the set of rolls for rolling the flange edges, employed in the third step of the process, Fig. 4 shows a set of rolls for rolling an unfinished U beam with outwardly bent flanges, employed in the first step of the process, and Fig. 5 shows a set of rolls for straightening out the U beam flanges and for rolling their edges, employed in the second and third step of the process.

According to the present invention the flanges are alternately bent outwardly and straightened so that flanges are at right angles to the web when the edges of the flanges are acted upon. This has the advantage that very strong direct rolling pressure is exerted upon the flanges which coincides with the direction of the plane in which the flanges extend during the rolling of the edges, resulting in a strong working through and compression of the material of the flanges. The improved method may be carried out in the following manner. The beam passes first the stand of universal rolls shown in Fig. 1, whereby the flanges are given the known inclined position with regard to the web by the horizontal rolls *a* and *b* and the vertical rolls *c* and *d*. The double Y shaped beam now passes through the universal rolling mill shown in Figs. 2 and 3, which may be placed immediately behind the first rolling stand containing the rolls shown in Fig. 1. During the forward pass the flanges are straightened as shown in Fig. 2 by the action of the vertical rolls *h* and *g*. During the next pass the beam returns through the same stand. During this operation the vertical rolls *h* and *g* are moved away as shown in Fig. 3, and the edges of the flanges *i*, *i*, *i*, *i*, are acted upon by the horizontal rolls *e* and *f*. The beam then passes again through the first stand

whereby the straightened flanges are again bent outwardly by the inclined faces of the horizontal rolls *a* and *b*. This process is repeated until the beam has been rolled out to the required size.

In applying the improved method to the rolling of U-iron, the rolling may be carried out as follows:—The U-iron passes first through a set of universal rolls of the kind shown in Fig. 4 whereby the thicknesses of the web and the flange portions are reduced, the flanges being in their inclined position. The U-iron then passes the second universal mill shown in Fig. 5 in which the flanges are straightened by two vertical rolls, and are rolled in their straightened position. The edges or faces *K*, *k* of the top horizontal roll are laterally slideable upon the main body *l* and are adjusted after each pass in such a manner as to engage closely the profile of the U-iron. The U-iron then returns through the same roll and passes again through the first stand in which the flanges are again bent outwardly. This operation is repeated until the U-iron is rolled to the required size. It will be seen that in this case the edges of the flanges are worked upon in the direction of the rolling pressure.

I claim:

Process for rolling of bars or girders of the I, H and U or like sections in universal rolling mills, consisting in alternately bending out and straightening the flanges and in simultaneously rolling the web and the flanges, each in a direction transverse to its respective plane when the flanges are bent out, and in rolling the edges of the flanges in the direction of their respective planes when the flanges are straightened out.

In testimony whereof I have signed my name to this specification in the presence of two subscribing witnesses.

JOHANN PUPPE.
